UNITED STATES PATENT OFFICE.

EDWARD G. ACHESON, OF NEW YORK, N. Y., ASSIGNOR TO ACHESON CORPORATION, OF NEW YORK, N. Y., A CORPORATION OF DELAWARE.

FILTER.

1,193,333.

Specification of Letters Patent.

Patented Aug. 1, 1916.

Application filed March 3, 1916. Serial No. 81,983.

To all whom it may concern:

Be it known that I, EDWARD G. ACHESON, a citizen of the United States, residing at New York, in the county of New York and State of New York, have invented certain new and useful Improvements in Filters, of which the following is a specification.

This invention is a filter intended primarily for household use, although applicable to other purposes.

The object of the invention is to provide a simple and inexpensive filter which is highly effective for the removal of suspended impurities from water, and is very easily, quickly and perfectly cleansed.

A preferred embodiment of the invention is illustrated in the accompanying drawing, wherein the figure is a central vertical section of a filter element with its mounting.

20 The filtering member proper, in the embodiment of the invention chosen for illustration, comprises a relatively thin and preferably slightly arched septum 1 of a suitable porous material, having formed integral therewith an encircling ring or flange 2, hereinafter referred to as the "bearing member." As shown, this bearing member is of such depth that the septum 1 is entirely comprised between its upper and lower planes. The bearing member therefore serves as a protection for the more fragile septum in every position; and moreover, the filter members can be safely stacked for storage or transportation. The bearing member 2 is preferably of the same permeable material as the septum 1, but is of such dimensions that the passage of water to its periphery under conditions of use is negligible. If desired, the bearing member 2, or portions of it, may be rendered impermeable to water, as by impregnation with paraffin or other suitable material.

The mounting illustrated comprises upper and lower members 3 and 4, preferably of cast iron or other metal, and adapted to be clamped upon the upper and lower bearing planes of the ring 2 by peripheral bolts 5 or equivalent elements. Gaskets 6 may be used to prevent leakage and to avoid danger of fracturing the bearing member, although these may be unnecessary when the bearing surfaces are true planes. The upper

member 3 is attached to the source of water-supply under pressure, the water entering through pipe 7, while the filtered water escapes through the orifice 8. It will be observed that the pressure of the water is exerted against the convex side of the arched septum 1, so that the latter may be made very thin while yet capable of withstanding very considerable pressures.

In order that the position of the filter member may not be accidentally reversed when replacing it in the mounting, I prefer to provide on one of its surfaces an annular rib 9, engaging a corresponding groove 10 in one of the elements of the mounting, the construction serving also to center the filter member. Of course any other means for making the position of the filter member irreversible may be used, or such means may be dispensed with.

The invention as disclosed in the present application relates primarily to the structural features of the filter, as distinguished from the material thereof. While the septum and its encircling bearing member may be formed of burned clay, biscuit ware, unglazed porcelain, or any of the other usual ceramic filtering media which are applicable to the construction of such forms, I prefer in all cases to form the filter member from clay or other amorphous substance which has been subjected to a process of partial or complete deflocculation and thereafter baked or fired, as described and claimed in my copending application, Serial No. 81,984 filed herewith.

It will be observed that in this construction there is no possibility of the passage of water to the discharge orifice 8, except through the filtering septum. Since there is no joint between the septum 1 and the bearing member 2, any leakage past the filter member, or through the joints between the filter-member and its mounting, would merely flow to waste without danger of contaminating the filtered water.

I claim:

1. A filter element comprising a porous ceramic septum, and a surrounding bearing member integral therewith, said bearing member of greater thickness than said septum.

2. A filter element comprising a porous ceramic septum, and a surrounding bearing member integral therewith, said bearing member of greater thickness than said septum, and said septum wholly comprised between the upper and lower planes of said bearing member.

3. A filter element comprising an arched, porous septum, and a surrounding bearing member integral therewith, said septum wholly comprised between the upper and lower planes of said bearing member.

In testimony whereof I affix my signature.
EDWARD G. ACHESON.
